Primary Examiner — Dominic V Simone(74) Attorney, Agent, or Firm — Banner & Witcoff, Ltd.(57) CLAIM

The ornamental design for a shoe, as shown and described.

DESCRIPTION

FIG. 1 is a side view of a shoe showing my new design;
FIG. 2 is an opposite side view thereof;

FIG. 3 is a top view thereof;

FIG. 4 is a rear perspective view thereof;

FIG. 5 is a second rear perspective view thereof;

FIG. 6 is a side view of a shoe showing an alternative embodiment of my new design;

FIG. 7 is an opposite side view thereof;

FIG. 8 is a top view thereof;

FIG. 9 is a front perspective view thereof; and,

FIG. 10 is a second front perspective view thereof.

The broken lines immediately adjacent to the shaded area define the bounds of the claimed design and form no part thereof. The broken lines depicting the remainder of the shoe show features that form no part of the claimed design.

1 Claim, 10 Drawing Sheets(56)
